HAIRDRESSING TOOL

Herman C. Schlicker, Brooklyn, N. Y., assignor
to Rollocurl Corporation, New York, N. Y., a
corporation of New York

Application February 18, 1939, Serial No. 257,181

24 Claims.

(Cl. 132—33)

The present invention relates to hair-dressing tools, and is more particularly directed toward hair-dressing tools having a mandrel slotted to receive a disappearing comb so that hair may be wound about the mandrel to form a curl.

In hair-dressing tools of the type referred to the disappearing comb is adapted to be in an exposed position for combing the ends of the lock of hair and assisting in starting the winding of the curl, or to be housed in the mandrel so that the wound coil of hair may be readily removed from the mandrel.

According to the present invention the disappearing comb is adapted to be moved laterally in and out of a slot in the mandrel without any accompanying longitudinal motion, this movement being preferably accomplished by pushing on one or the other of two exposable presser pieces engageable by the thumb or finger. The disappearing comb insert can be pushed from the exposed position toward the housed position, or from the housed position towards the exposed position, and when it has passed beyond the mid-position an energy storing spring acts to complete the movement. The end of the comb insert remote from the actuating spring and the opposed portions of the sheath or mandrel are provided with interlocking elements so arranged that, while they do not interfere with assembling the device when it is manufactured, they prevent the accidental dislodgment of this end of the comb from the sheath.

The present invention also contemplates that the sheath or mandrel and the movable insert have long transverse bearing surfaces which insure that the insert will move parallel with itself and have a minimum tendency to tilt.

The present invention also contemplates that the hair-dressing device shall have a device for holding a hairpin in position to receive the coil of hair as it is removed from the mandrel.

Other and further objects will appear as the description of the invention proceeds.

The accompanying drawings show, for purposes of illustrating the present invention several embodiments in which the invention may take form, it being understood that the drawings are illustrative of the invention rather than limiting the same.

In these drawings:

Figures 1 and 2 are side elevation and top plan views of a hair-dressing tool embodying a disappearing comb, parts being broken away to show interior construction;

Figure 3 is a section on the line 3—3 of Figure 1;

Figure 4 is a fragmentary view of a detail at an enlarged scale;

Figures 5 and 6 are side elevation and top plan views of a modified form of hair-dressing tool embodying a disappearing comb, parts being broken away to show interior construction;

Figure 7 is a transverse sectional view on the line 7—7 of Figure 5;

Figures 8 and 8a are side elevation and top plan views of a modified form of hair-dressing tool embodying a disappearing comb, parts being broken away to show interior construction;

Figure 9 is a side elevational view with parts broken away showing a further modified form of construction;

Figure 10 is a top plan view of the structure shown in Figure 9;

Figure 11 is a fragmentary sectional view on the line 11—11 of Figure 10;

Figure 12 is an end elevational view of the device of Figures 9 and 10;

Figures 13 and 14 are sectional views taken on the line 13—13 of Figure 9; and

Figure 15 is a sectional view on the line 15—15 of Figure 9.

In the arrangement shown in Figures 1, 2 and 3, the hair-dressing device has a body member 20, one end of which is provided with a handle 21, provided with teeth if desired, while the other end is in the form of an oval mandrel having a transverse slot 22. This slot opens both ways and may be of uniform width throughout its length, as indicated in Figure 2, except for the provision of grooves 23 in the side walls of the slot. These grooves open downwardly or rearwardly, as shown in Figures 1 and 3, and provide stops 24 near the upper or outer opening of the slot 22. These stops cooperate with laterally extending elements 25 carried by the disappearing comb insert 26 which increases the width of the backing of the insert so that the outer or left end of the insert cannot be moved upwardly to project beyond the sheath or mandrel.

It will be noted that the teeth on the insert or comb member extend all the way to its end and that the end of the insert extends all the way to the end wall of the slot in the sheath or body member, so that the teeth may be very near the end of the device. As ringlets are made by turning or rotating the device with the end bearing on the scalp, it is possible by this construction to insure that the outer end of the comb member is at all times retained in the

slot.

As the insert 26 is moved laterally, the teeth will be held in the side walls of the slot 22, and the stops 24 will prevent the outer end of the insert from being moved upwardly to project beyond the sheath or mandrel.

As the teeth are held in the side walls of the slot 22, the side walls of the slot will bear against the outer end of the insert 26, and the stops 24 will prevent the outer end of the insert from being moved upwardly to project beyond the sheath or mandrel.

As the teeth are held in the side walls of the slot 22, the side walls of the slot will bear against the outer end of the insert 26, and the stops 24 will prevent the outer end of the insert from being moved upwardly to project beyond the sheath or mandrel.

sheath and yet the teeth are very close to the scalp, so that tighter ringlets can be made than where the teeth of the disappearing comb are farther away from the scalp.

5 The insert is provided with two oppositely extending finger pieces 27 and 28, and has an opening 29 which receives a bowed spring 30 and a transversely extending pin 31. The pin is secured to the body member 20 and the opening 29 has 10 upper and lower stops 32 and 33 to limit the extent of movement of the comb bearing member. The spring 30 presses against the pin 31 and insures that the right-hand end of the insert 26 will bear against the right-hand end of 15 the slot 22. When the insert is pushed from the full line position toward the dotted line position of Figure 1, the spring 30 is compressed until the center 34 of the spring passes by the pin 31, whereupon the spring will tend to expand and will 20 facilitate the completion of the movement of the insert. The end of the insert is brought against a stop 35 provided in the body member.

The arrangement shown in Figures 5, 6 and 7 employs a body member 40 having an upwardly opening slot 41 adapted to receive a disappearing comb insert 42 somewhat similar to that of Figure 1. In making the body member 40 it is cored out, so as to have downwardly opening passages 43 and upwardly opening passages 44 which provide an opening for the width increasing elements 45 carried by the insert 42. The inwardly extending ledge 46 acts as a stop to limit the extent to which the insert can project out of the sheath. The insert is provided with a slot 47 to 30 receive a transverse pin 48 carried by the body member 40, which limits the extent of movement of the insert and which provides a bearing surface to limit movement of the insert to the left. The body member is provided with a pocket 49 to 35 receive a coiled spring 50 and ball 51, and the ball is pressed into one or the other of the recesses 53 or 54. The end of the insert fits closely the end of the slot, so that the insert must move parallel with itself.

40 In the arrangement shown in Figures 8 and 8a, the body member 60 has a slot 61 adapted to receive a disappearing comb insert 62. The left end of the insert has a pin 63 cooperative with a bayonet slot 64 in the body member for the purposes above described. Here the end of the insert carrying the finger pieces 65 and 66 is provided with intersecting oblique slots 67 adapted to receive the end 68 of a spring 69 which is anchored to the body member by a suitable pin, as 45 indicated at 70. Pressing on the finger piece will cause the spring 69 to be tensioned until the peak of the slot has been passed, whereupon the spring will facilitate completion of the movement of the insert to the projected or retracted position. The 50 spring acts to hold the end of the insert against the bearing surfaces provided in the end of the slot.

In the arrangement shown in Figures 9 to 15, the body member 71 is provided with a slot 72 65 adapted to receive the toothed insert 73. The interlocks at the left end of the insert and body member may be the same as shown in Figures 5 and 6 and the same reference characters are applied.

70 The insert has finger pieces 74 and 75 somewhat wider than the slot 72, so that bearing surfaces are provided, as indicated at 76, 77 and 78. The insert is urged toward the left, as shown in Figure 75 9, by a spring indicated at 79, and this spring is

secured in place by a keeper member 80 held in place by a pin 81, as indicated.

The body member or sheath 71 is provided with an extension 82 beyond the end of the disappearing comb, and this extension is provided with an eccentrically located opening 83 below the bottom of the slot 72 in the case or body member which receives the insert. The extension 82 is provided with a bump or protuberance 84 which extends through substantially 180°, as shown in Figure 10.

When a hairpin, such as a bob pin of the standard shape, shown at 85, is employed the smooth shank 85a of the bob pin is inserted in to the opening 83, and when the wavy or sinuous shank 85b is brought to the position shown in Figure 11, the first wave or hump of the bob pin will come to rest on the bump or protuberance 84 and the bob pin will be securely held in this position, so that the hair can be combed out and wound about the mandrel without any interference by the pin. As the pin is pushed in from the position shown in Figure 11 to the dot-and-dash line position of Figure 9, the smooth shank 85a passes through a slot 86 provided in the bottom of the comb receiving slot 72, and the bump or protuberance 84 will cause the shank to spread, as indicated. When the bob pin is pushed all the way in, the oblique portion 85c of the bob pin is brought against the bump or protuberance 84, thereby effecting a very much wider opening of the exposed shank of the bob pin without, however, impairing the tension in the spring so that it may be repeatedly used for the purpose. The bob pin can be turned through about 180°, as indicated in Figure 12, so as to place it at the desired orientation. It cannot be turned all the way around the shank as will be obvious, and in order to provide positive stops to limit the extent of movement one can provide small protuberances as indicated at 87. The extension 82 is tapered, as indicated at 88, so that removal of the wound coil past the protuberance 84 is facilitated.

Where the pin holding device shown in Figures 9 to 15, inclusive, forms part of a hair-dressing tool having a disappearing comb, the stationary parts will generally be made out of a single piece of molded plastic. It will be understood, however, that certain features of the pin holder may be employed in other forms of hair-dressing tool than those utilizing disappearing combs.

It is obvious that the invention may be embodied in many forms and constructions within the scope of the claims and I wish it to be understood that the particular forms shown are but a few of the many forms. Various modifications and changes being possible, I do not otherwise limit myself in any way with respect thereto.

What is claimed is:

1. In a hair curling device, a sheath having a longitudinally extending laterally opening slot and an end wall, and a comb having teeth and a backing both extending to the end wall, the comb being laterally movable in the slot between projected and housed positions, the width of the backing being substantially the width of the slot, the backing of the comb having a laterally extending element, the slot wall being cut away to receive the laterally extending element and having an overlying element to limit the movement of the comb outwardly.

2. In a hair curling device, a sheath having a longitudinally extending laterally opening slot and an end wall, and a comb having teeth and a backing both extending to the end wall, the

5 comb being laterally movable in the slot between projected and housed positions, the width of the backing being substantially the width of the slot, the backing of the comb having a laterally extending element, the sheath having, in the plane of movement of the comb, a bayonet slot communicating with the comb-receiving slot adapted to receive the laterally extending element to limit outward movement of the comb.

10 3. In a hair curling device, a sheath having a longitudinally extending laterally opening slot and an end wall, and a comb having teeth and a backing both extending to the end wall, the comb being laterally movable in the slot between projected and housed positions, the width of the backing being substantially the width of the slot, and backing of the comb having a laterally extending element, the sheath wall adjacent one end having an opening to receive said lateral extension in the comb, the opening having a wall adjacent the outer edge of the slot to limit outward movement of the comb.

15 4. A hair curling device having a slotted sheath having an end wall and a disappearing comb movable in the slot between housed and projected positions, the comb having teeth and a backing both extending to the end wall, the backing having adjacent the end thereof a width increasing element, the slot in the sheath having an increased width for a part only of its depth to accommodate said element and limit its movement toward projected position.

20 5. A hair curling device as in claim 4, wherein the sheath walls forming the slot are disconnected except at their ends and have rearwardly opening grooves to receive the width increasing element on the comb.

25 6. A hair curling device as in claim 4, wherein the slot opens both ways near the end of the sheath and only a portion of said slot has a width to admit the comb with width increasing element, said portion being spaced from the end of the slot.

30 7. A hair curling device having a sheath formed with a longitudinally and transversely extending slot open at both sides of the sheath, the sheath having ends forming an end wall of the slot, the inner face of the slot being grooved from one side of the sheath nearly to the other, and a comb having teeth and a backing both extending to the end wall of the slot, the comb being carried in the slot for movement between housed and projected positions and having a lateral extension opposite the end thereof received in the groove and limiting the movement of the comb in the slot.

35 8. A hair curling device having a slotted sheath, a disappearing comb laterally movable in the slot between housed and projected positions, the disappearing comb having thumb-pieces one of which is exposed to be accessible to actuate the comb to the other position, the sheath and comb having cooperative guides to permit lateral movement and prevent longitudinal movement, a spring, and means acting when either movement is commenced to deform the spring and hold it deformed until the movement is nearly completed whereupon the spring is released so that the comb is held in the position toward which it is moved by the thumb-piece.

40 9. A hair curling device having a slotted sheath, a disappearing comb laterally movable in the slot between housed and projected positions, the disappearing comb having thumb-pieces one of which is exposed to be accessible to actuate

45 the comb to the other position, the end of the comb slidably engaging the end wall of the slot, the sheath carrying a cross member entering an aperture in the comb and engaging a wall of the aperture to hold the end of the comb against the end of the slot in the sheath, the comb carrying a spring engageable with the cross member and deformed when the comb is pushed toward mid-position and released when the comb passes mid-position.

50 10. A hair curling device comprising a sheath having a longitudinally extending laterally opening slot with an end wall at right angles to the direction of the slot, a member extending across the slot in the sheath adjacent the said end wall, a tooth bearing insert slidably received in the slot, the insert having an end wall to fit the end wall of the slot and an aperture provided with a wall parallel with the said end wall and spaced to engage the cross member when the end wall of the insert engages the end wall of the slot, and a bowed spring carried in the aperture and bearing against the cross member to hold the insert in either extreme position.

55 11. A hair curling device as in claim 10, wherein the insert has oppositely extending thumb-pieces at the apertured end to facilitate shifting the insert.

60 12. A hair curling device comprising a slotted sheath, a toothed insert extending lengthwise of the slot, means to guide the insert for movement laterally of the slot and for preventing longitudinal movement, stops limiting the movement in each direction, a spring, means operative to tension the spring when the insert is shifted to mid-position to store energy in the spring so that after mid-position is passed the spring is effective to complete the movement, and a locking piece engaging one end of the spring and acting as one of the stops.

65 13. A hair curling device comprising a sheath having a longitudinally extending laterally opening slot provided with an end wall at right angles to the direction of the slot, the sheath having a short slot opposite the long slot adjacent said end wall to form a transverse passage with a guide wall spaced from the end wall, a tooth bearing insert extending lengthwise of the long slot and having an end wall engaging the end wall of the slot and oppositely extending thumb-pieces one of which has a wall engaging the guide wall of the sheath, the insert having two intersecting oblique slots, and a tension spring anchored to the sheath beyond said slot end wall and engaged in said oblique slots for holding the insert in the position to which it has been moved.

70 14. A hair curling device comprising a slotted sheath, a toothed insert extending lengthwise of the slot, means to guide the insert for movement laterally of the slot and for preventing any other movement, stops limiting the movement in each direction, and spring means holding the insert in its extreme positions.

75 15. A hair curling device comprising a slotted sheath, a toothed insert extending lengthwise of the slot, means to guide the insert for movement laterally of the slot and for preventing any other movement, stops limiting the movement in each direction, a spring, and means operative to tension the spring when the insert is shifted to mid-position to store energy in the spring so that after mid-position is passed the spring is effective to complete the movement.

80 16. A hair-dressing tool comprising a sheath with a laterally opening slot, a manually pro-

tractable and retractable comb in said slot, guide means for guiding the comb between said two positions and preventing any other movement, said guide means including long bearing surfaces parallel to the direction of movement, and spring means acting to hold said surfaces in contact and for insuring completion of the shifting movement of the comb.

17. A hair curling device comprising a mandrel about which hair is adapted to be wound, the mandrel having an opening in its end adapted to slidably and rotatably receive one shank of a hairpin, the mandrel having a protuberance near the end adapted to enter into the hump near the end of the other shank of the hairpin to retain the hairpin against accidental dislodgment.

18. A hair curling device such as claimed in claim 17, wherein the protuberance extends part way around the axis of the opening and terminates in stops which limit the extent to which the hairpin may be rotated.

19. A hair curling device such as claimed in claim 17, wherein the opening in the mandrel is long enough to permit pushing the hairpin shank inwardly for substantially its entire length, the protuberance acting to spread the shanks apart.

20. A hair curling device such as claimed in claim 17, wherein the mandrel has a comb receiving slot and the protuberance is so placed as to retain the pin beyond the end of the slot, and having a disappearing comb insert in said slot.

21. A hair curling device comprising a longitudinally slotted mandrel, a disappearing comb insert laterally movable in the slot, the mandrel having an extension beyond the end of the slot, the extension having a longitudinally extending opening disposed below the bottom of the insert

when retracted and adapted to receive a shank of a hairpin, the extension having a protuberance adapted to tension the hairpin and hold it slightly spread when the tip only of the shank is inserted, and to spread the shanks widely when the shank is fully inserted, the protuberance having a contour to hold the shanks separated throughout a portion of the arc about the axis of the opening and to prevent complete rotation.

22. In a hair-dressing tool, a hair receiving mandrel having an axially extending opening, and a bob pin having a straight shank insertible into and rotatable in said opening and a sinuous shank, the mandrel having a bump near the end adapted to be gripped by the sinuous shank and hold it against removal.

23. In a hair-dressing tool, a hair receiving mandrel having an axially extending opening, and a bob pin having a straight shank insertible into and rotatable in said opening and a sinuous shank provided with an oblique portion near the loop, the mandrel having a bump near the end adapted to be gripped by the sinuous shank and hold it against removal, the bump engaging the oblique portion of the shank and spreading the shank farther away from the mandrel.

24. A hair dressing tool comprising a pair of substantially parallel spaced apart walls defining between them a sheath, a comb, slidably housed in said sheath, means for projecting the comb from its sheath, a pin projecting laterally from one side of the back of said comb, near its outer end, one end of the sheath being provided with a slot for slidably receiving said pin, said slot having a shoulder for limiting the outward movement of said pin.

HERMAN C. SCHLICKER.
